UNITED STATES PATENT OFFICE

CHARLES W. PURNELL, OF NATCHEZ, MISSISSIPPI, ASSIGNOR OF ONE-HALF TO GEORGE C. MOORE, OF NATCHEZ, MISSISSIPPI

APPARATUS FOR LANDING AND HOUSING DIRIGIBLES

Application filed September 23, 1929. Serial No. 394,578.

This invention relates to an apparatus for landing and housing dirigibles, the general object of the invention being to provide means whereby a dirigible can be landed and placed in a hangar and removed from the hangar. 5 by a small landing crew, such means consisting of a track and a number of cars having their wheels engaging the rails of the track in such a manner that there is no danger of the cars being lifted from the rails, with 10 motor driven means on each car for operating a drum to which a cable of the craft is connected and for moving the car along the track. 15 Another object of the invention is to provide clutch means for connecting the drum with and disconnecting it from the motor, with manually operated ratchet means for preventing retrograde movement of the drum until the cable is to be unwound therefrom 20 and clutch means for connecting and disconnecting the driving means of each car with the motor. 25 A still further object of the invention is to provide means whereby the cables are connected with the interior framework of the craft and can be passed through port holes in the sides of the body so that each side of the craft is attached by the cables to a number of cars arranged on a track at each side of 30 the craft, whereby the craft is prevented from moving sidewise even in high winds as well as vertical movement, so that the craft can be moved into the hangar without danger of injuring the craft. 35

This invention also consists in certain other features of construction and in the combination and arrangement of the several parts, to be hereinafter fully described, illustrated in 40 the accompanying drawings and specifically pointed out in the appended claims.

In describing the invention in detail, reference will be had to the accompanying drawings wherein like characters denote like or 45 corresponding parts throughout the several views, and in which:—

Figure 1 is a top plan view showing a craft attached to the cars so that the craft can be moved into its hangar, the hangar being 50 shown in section.

Figure 2 is an elevation of Figure 1.

Figure 3 is a section on line 3—3 of Figure 4.

Figure 4 is an elevation of one of the cars and a portion of the track.

Figure 5 is a top plan view of one of the 55 cars and a portion of the track.

Figure 6 is a sectional view through the drum and its associated parts.

Figure 7 is a sectional view through the 60 clutch means for connecting the drive gear on the motor shaft to said shaft.

Figure 8 is a sectional view on line 8—8 of Figure 3.

Figure 9 is a section on line 9—9 of Figure 65 3.

Figure 10 is a section on line 10—10 of Figure 4.

Figure 11 is a section on line 11—11 of Figure 10.

Figure 12 is a section on line 12—12 of 70 Figure 3.

Figure 13 is a section on line 13—13 of Figure 3, and showing how the lug on the drum engages and releases the cable.

Figure 14 is a fragmentary side view showing how two rails of the track are joined together.

Figure 15 is a perspective view, with parts broken away, of one end of one rail.

Figure 16 is a similar view of one end of the adjacent rail.

In these drawings, the letter A indicates a pair of tracks which extend from a point adjacent the rear of the hangar B to any desired point in front of the hangar, these tracks having the bumpers or stops 1 at their ends and each track comprises a pair of rails 2 of I shape in cross section, with the lower portions of the rails embedded in a concrete 90 foundation 3, the lower flanges of the rails having the anchor members 4 passing through them, these anchor members being also embedded in the foundation.

A plurality of cars C is arranged on each 95 track, each car comprising a platform 5 having a hanger 6 at each corner thereof and a hanger 7 at each side thereof. These hangers are preferably of inverted U shape with their bights resting on portions of the platform 100

and bolted thereto and their limbs depending from the platform, with some of the limbs passing through openings in the platform. Each corner hanger supports the four roller-like wheels 8, two of the wheels engaging the top of the rail and the other two engaging the lower surface of the top part of the rail, as clearly shown in Figure 3. Each of these wheels is mounted on a stationary axle 9 fastened to the hanger, with roller bearings 10 between the inner circumference of the wheel and the axle and I prefer to fasten the axle to the hanger by a key 11, as shown in Figure 10. Each of the hangers 7 also carries four wheels for engaging the upper and lower faces of the tread part of a rail, with the upper pair of wheels 12 keyed to a shaft 13 which passes through both hangers 7 and is suitably journaled in the hangers, roller bearings 14 being provided for the shaft to reduce friction. The two lower wheels 15 in each bearing 7 are each carried by a stub shaft 16 fastened to the hanger, with roller bearings 17 between the wheel and shaft to reduce friction. Each wheel 12 is connected with a wheel 15 by the gears 18 which are fastened to the wheels, so that the lower wheels are driven from the upper wheels and as these upper wheels are fastened to the shaft 13, these upper wheels will be driven from said shaft.

A motor M is supported by the platform and its shaft 19 has its ends journaled in the uprights 20 carried by the platform. A pinion 21 has its hub 22 rotatably arranged on a portion of the shaft 19 and said hub has clutch teeth at its outer end which are adapted to be engaged by the clutch teeth on a clutch collar 23 which is slidably but non-rotatably connected with the shaft 19 by the keys 24. A ring 25 is rotatably arranged in the groove in said collar and said ring is connected to a hand lever 26 by the pin and slot connections 27 so that by manipulating the lever, the clutch collar can be moved into operative and inoperative position. The pinion 21 meshes with an idle gear 28 carried by the platform and this gear 28 meshes with a gear 29 fastened to the shaft 13 so that when the clutch is in operative position, the shaft 13 will be driven from the motor and thus the wheels carried by the hangers 7 will be rotated to cause movement of the car on the track. The motor, of course, is a reversible one and is controlled in the ordinary manner from the controller box D. Current is supplied to the motor from the third rail 30 placed in a conduit 31 formed in the foundation between the rails of each track 60 through the shoe carrying member 32 connected with the carriage and passing through the slot 33, with the shoes engaging the third rail, these shoes being electrically connected with the motor.

65 A drum 34 is rotatably arranged on the

shaft 19 and is adapted to be connected with and disconnected from the shaft by the clutch means, shown generally at 35, and which are moved into operative and inoperative position by the lever 36. A dog 37 engages a ratchet wheel 38 on the drum to hold the drum against retrograde movement, the dog being provided with a handle 39 for moving it into operative and inoperative position and a spring 40 acts to hold the dog in either one of its two positions after the dog has been moved by hand.

A hook-shaped lug 41 is carried by the drum for receiving the eye 42 of a cable 43 so that when the eye is placed over the lug, 80 as shown in full lines in Figure 13 and the drum rotated, the cable will be carried around with the drum and thus be wound thereon, and when the cable is being unwound from the drum, the eye will slip off of the lug at the 85 end of the unwinding action, as shown in dotted lines on the right side of Figure 13.

A brake, shown generally at 44 in Figure 3, is provided for the shaft 13, the band of this brake being contracted and expanded 90 through means of a hand lever 45 so that an operator on the car can apply the brake when it is desired to brake the car.

The cables 43 pass through port holes 46 in the sides of the dirigible D and are fastened 95 to the interior framework.

The various parts can be lubricated in any suitable manner, the drawings showing cups 47 and Figure 6 shows a tube 48 passing from one side of the drum to a space 49 between 100 the axle and the central tubular part of the drum, so that lubricant inserted into the tube 48 will reach the space and thus lubricate the parts.

The rails are connected together by forming a dovetail notch 50 in an end of one rail to receive a dovetail projection 51 on the end of another rail and then the ends of the rails are welded together so that the rails are firmly connected together.

110 Thus it will be seen that when a dirigible wishes to land, it is simply necessary for members of the crew thereof to throw the cables 43 through the port holes 46 to enable the ground crew to seize the cables and attach 115 them to the drums. Then an operator on each car shifts the lever 36 to connect the drum with the motor, whereby the cables will be wound upon the drums and the craft lowered to a position where it can enter the hangar. 120 The dogs 37, engaging the ratchets 38, will prevent unwinding of the cables from the drums and then the drums are released from the shaft, after which another operator manipulates the lever 26 to connect the pinion 21 with the motor shaft so that this pinion will cause the gears 28 and 29 to drive the shaft 13 which in turn will impart movements to the drive wheels 12 and 15 so that the cars will be propelled along the tracks 125 130

and thus carry the dirigible into the hangar. All the cars should have the parts adjusted to travel at the same speed so that they will keep their relative positions and when the 5 cars are not in motion, the brakes 44 should be applied to prevent them from moving while the cables are being attached to the drums or detached therefrom and while being wound on or unwound from the drums.

10 Attention is called to the fact that a number of cars is attached by the cables to each side of the craft, as shown in Figures 1 and 2, so that the craft is held against sidewise movement and can be properly handled even 15 in high winds.

Attention is also called to the fact that the parts are so constructed and arranged as to withstand the strain of the upward pull exerted on them by the dirigible, as each rail is 20 practically of one piece and the rails are firmly anchored in their foundations and each car is held on its track by six sets of roller-like wheels, with one pair of each set engaging an under part of a rail. The 25 wheels are also firmly connected with the platform of the car by the hangers which pass through portions of the platform.

When the craft is to be used, the cars are run out of the hangar and then the drums are 30 released from the drive shafts by moving the dogs 37 to inoperative position, so that the strain on the cables will rotate the drums in a reverse direction, thus permitting the cables to unwind from the drums, the eyes passing 35 off the lugs when the cables are fully unwound from the drums, as before explained and as shown in detail in Figure 13. Then the cables are pulled through the port holes by the crew of the craft and coiled in the 40 body ready for use again when the craft is to land. As before stated, with this invention, a small ground crew can handle the ship. For instance, where it takes from 600 to 900 men to handle a ship, with this invention, about 25 men can handle a ship. Of 45 course, this depends on the length of the ship and the number of cars used. It is preferable to have two men on each car, one to operate the lever for the drum and the other 50 the lever for connecting the propelling wheels to the motor, with a man at each side of the car and a captain for the men.

It is thought from the foregoing description that the advantages and novel features 55 of the invention will be readily apparent.

It is to be understood that changes may be made in the construction and in the combination and arrangement of the several parts, provided that such changes fall within 60 the scope of the appended claims.

What I claim is:—

1. In combination with a dirigible and its hangar, a pair of tracks extending into the hangar, a number of cars on each track, 65 a drum on each car, a number of cables ex-

tending through each side of the ship, the cables on one side of the ship being adapted to be connected with the drums of the cars on one track and the cables on the opposite side of the ship adapted to be connected with the drums of the cars on the other track, means for rotating the drum on each car to wind a cable thereon and propulsion means for each car.

2. In combination with a dirigible and its hangar, a pair of tracks extending into the hangar, a number of cars on each track, a drum on each car, cables extending through one side of the ship and adapted to be connected with the drums on the cars on one track, cables extending through the other side of the ship and adapted to be connected with the drums of the cars on the other track, a motor on each car, clutch means for connecting the drum to the motor and means including clutch means for driving some of the wheels of the car from the motor.

3. In an apparatus for landing dirigibles, a track, a car on said track, each rail of the track having its upper part of T shape, a plurality of sets of roller-like wheels carried by the car, a pair of each set engaging the under face of a rail and another pair of each set engaging the upper face of the rail and power means for rotating the wheels of some of the sets to propel the car along the track.

4. In an apparatus for landing dirigibles, a track, a car on said track, each rail of the track having its upper part of T shape, a plurality of sets of roller-like wheels carried by the car, a pair of each set engaging the under face of a rail and another pair of each set engaging the upper face of the rail, power means for rotating the wheels of some of the sets to propel the car along the track, such means comprising a driven shaft connected with the upper wheels of the driven sets and gearing connecting these pairs of wheels with the lower pairs.

5. In a dirigible landing device, a track, a car thereon, a drum on the car, a number of hangers at each side of the car, an upper pair and a lower pair of wheels carried by each hanger, the lower pair engaging the under face of a rail and the upper pair the upper face thereof, a shaft journaled in the two central hangers and connected with the upper pairs of wheels of said hangers, gears connecting the upper pair of wheels of these hangers with the lower pair thereof, a motor on the car, means, including clutch means, for connecting the motor with the shaft and clutch means for connecting the motor with the drum.

6. In combination with a dirigible and its hangar, said dirigible having ports in its sides, cables connected with the interior framework of the dirigible and adapted to be passed through the ports, a pair of tracks extending into the hangar, a number of cars

on each track, a drum on each car, the cables being adapted to be connected with the drums when dropped through the ports, means for rotating the drums to wind the cables thereon, means for propelling the cars to move the dirigible into and out of the hangar, manually operated ratchet means for each drum for preventing unwinding of the cable thereon, but when moved to inoperative position permitting the cable to unwind therefrom.

7. In combination with a dirigible and its hangar, a pair of tracks extending into the hangar, a number of cars on each track, winding means on each car, cables extending through ports in the sides of the ship and adapted to be connected with the winding means of the cars, the cables extending from one side of the ship being connected with the cars on one track and the cables at the other side of the ship being connected with the cars on the second track.

In testimony whereof I affix my signature.
CHARLES W. PURNELL.
